UNITED STATES PATENT OFFICE.

FRANZ ABELS, OF BREMEN, GERMANY.

STEAM-TRAP.

1,086,260.

Specification of Letters Patent.

Patented Feb. 3, 1914.

Application filed June 13, 1912. Serial No. 703,498.

To all whom it may concern:

Be it known that I, FRANZ ABELS, a subject of the German Emperor, and resident of Bremen, Germany, have invented certain new and useful Improvements in Steam-Traps, of which the following is a specification.

The present invention relates to a steam trap designed to be applied to any apparatus in which steam is used as a heating means, and which comprises a tubular casing within which the cooled, water loaded steam flowing back from the heating apparatus, passes through a plurality of superposed ducts formed by nearly annular grooves provided in the periphery of a central core which tightly fits the tubular receptacle. Said ducts or grooves are not wholly circular, as a rib, extending longitudinally from one end to the other of said core is left, so that each groove separately is provided with a baffle, said baffles being of course superposed all along the core. Each of said grooves is connected with the following one by means of a notch provided in the annular projection left between two superposed grooves, said notches being adjacent to the longitudinal rib and alternately disposed at the left and at the right hand of said rib. At top of said core and fitting said tubular casing is a movable steam regulating disk provided with an adjustable hole corresponding to the uppermost one of the above described notches and through which the watery steam enters the first groove in one direction flows through said groove, breaks against the rib which acts as a baffle, enters the following duct through the adjacent connecting notch, flows through said last duct in an opposite direction with respect to the foregoing one, breaks against the baffle of said duct, enters the following duct and so on through the whole device until it escapes at the lower end. By these means the steam is quickly condensed.

In the accompanying drawings Figure 1 is a side elevation partially in section of the steam trap. Fig. 2 is a top plan view of the core, the casing being in section. Fig. 3 is a bottom plan view of the core, the casing being in section. Fig. 4 is a view similar to Fig. 1, but illustrating the flanges of the core arranged at an angle.

In Figs. 1-3 *b* is a central core which

snugly fits in an annular casing *a* into which flows the steam from a heating apparatus. Integrally formed on the periphery of said core are spaced apart annular flanges, the spaces forming grooves *d*. Said grooves *d* do not extend entirely around the core, a rib *g* being left all along the core. A movable disk *h* provided on top of said core *b*, and provided with an adjustable hole *p* serves for regulating the jet of steam entering the trap. In the solid portions between the grooves *d* notches *c* are provided alternately at the left and at the right hand of the rib *g*, each of said notches connecting two superposed grooves. The steam flowing back from the heating apparatus enters the hole *p* of the regulating disk *h*, flows through the upper groove *d*, in the direction of the arrow *q*, and breaks against the corresponding portion of the rib *g* which acts as a baffle, enters the notch *c* at the right hand of said rib and then in the following groove *d* where it flows in the direction of the second arrow *r*, that is to say in an opposite direction with respect to the foregoing one, breaks against the corresponding baffle and so on until it escapes at the lower end of the separator, where the condensed water leaves the steam through a special duct.

In Fig. 4 the grooves *d'* instead of being constructively disposed with respect to the axis of the core as in Fig. 1, are helical.

Having now fully described my said invention, what I claim and desire to secure by Letters Patent, is:

A steam trap comprising a casing, an inlet pipe at the top of the casing, an outlet pipe at the bottom of the casing, a core mounted in the casing between the inlet and outlet pipes, said core having an integral radial rib which abuts against the inner wall of the casing, a plurality of spaced apart flanges, all of the same size and which are integral with and extend from the core to the inner wall of the casing, part of said plurality of flanges extending from the left side wall of the rib and terminating some distance from the right side wall of said rib to form exit openings, the remaining part of the plurality of flanges being interposed between the first mentioned part of said plurality of flanges and extend from the right side wall of the rib and terminate

some distance from the left side wall of said rib to form exit openings, the exit openings formed between the terminals of the flanges and the side walls of the rib being alternately disposed to form a circuitous passage through the casing and a movable disk formed at its edge with a notch to coöperate with the exit opening in the top flange to

control the flow of steam entering the circuitous passage.

In testimony whereof I have hereunto set my hand in presence of two witnesses.

FRANZ ABELS.
